(57) **CLAIM**

The ornamental design for a combination soap saver and palm brush, as shown and described.

DESCRIPTION

FIG. 1 is a top perspective view of a combination soap saver and palm brush, according to the present invention.

FIG. 2 is a bottom perspective view thereof.

FIG. 3 is a front view thereof.

FIG. 4 is a front perspective view thereof.

FIG. 5 is a left view thereof. The right view is a mirror image of the left view.

FIG. 6 is a top view thereof.

FIG. 7 is a bottom view thereof; and,

FIG. 8 is an exploded top perspective view thereof.

1 Claim, 8 Drawing Sheets
